CLAIM

The ornamental design for a wallpack light fixture, as shown
and described.

DESCRIPTION

FIG. 1 is a perspective of a wallpack light fixture showing
our new design;

FIG. 2 is a front elevational view of the wallpack light
fixture;

FIG. 3 is a top plan view of the wallpack light fixture;

FIG. 4 is a right elevational view of the wallpack light fixture;

FIG. 5 is a rear elevational view of the wallpack light fixture;

FIG. 6 is a bottom plan view of the wallpack light fixture;

and,

FIG. 7 is a left elevational view of the wallpack light fixture.
The broken lines shown in the figures are for the purpose of
illustrating portions of the wallpack light fixture and form no
part of the claimed design.

1 Claim, 7 Drawing Sheets
